(57) **CLAIM**

The ornamental design for lens for eyeglasses, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view showing a first embodiment of a lens for eyeglasses of the present invention;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is an end view taken along the line 7-7 of FIG. 1;

FIG. 8 is a front view showing the first embodiment of lens for eyeglasses in a state of use;

FIG. 9 is a front view showing a second embodiment of lens for eyeglasses;

FIG. 10 is a rear view thereof;

FIG. 11 is a top plan view thereof;

FIG. 12 is a bottom plan view thereof;

FIG. 13 is a left side view thereof;

FIG. 14 is a right side view thereof;

FIG. 15 is an end view taken along the line 9-9 of FIG. 9;

FIG. 16 is a front view showing the second embodiment of the lens for eyeglasses in a state of use;

FIG. 17 is a front view showing a third embodiment of the lens for eyeglasses;

FIG. 18 is a rear view thereof;

(Continued)

FIG. 19 is a top plan view thereof;
 FIG. 20 is a bottom plan view thereof;
 FIG. 21 is a left side view thereof;
 FIG. 22 is a right side view thereof;
 FIG. 23 is an end view taken along the line 17-17 of FIG. 17;
 FIG. 24 is a front view showing the third embodiment of the lens for eyeglasses in a state of use;
 FIG. 25 is a front view showing a fourth embodiment of the lens for eyeglasses;
 FIG. 26 is a rear view thereof;
 FIG. 27 is a top plan view thereof;
 FIG. 28 is a bottom plan view thereof;
 FIG. 29 is a left side view thereof;
 FIG. 30 is a right side view thereof;
 FIG. 31 is an end view taken along the line 25-25 of FIG. 25;
 and,
 FIG. 32 is a front view showing the fourth embodiment of the lens for eyeglasses in a state of use.
 The broken lines in FIGS. 2-7, 10-15, 18-23 and 26-31 illustrate portions of the article that form no part of the claimed design;
 The broken lines in FIGS. 8, 16, 24 and 32 depict environmental subject matter and form no part of the claimed design;
 The alternate long and short dash lines indicate boundaries of the claimed design and form no part thereof.
